WATCH BAND CLASP

Alfred Joseph Durante, Forest Hills, N.Y., assignor to
Cartier, Inc., New York, N.Y.

Filed June 12, 1974, Ser. No. 478,589

Term of patent 14 years

Int. Cl. D11—01

U.S. Cl. D45—4 A

FIG.1

FIG.2

FIG.3

FIG.4

FIG.5

FIG.6

FIG. 1 is a front elevational view of the watch band clasp showing my novel design;

FIG. 2 is a top plan view of the watch band clasp shown in FIG. 1;

FIG. 3 is a left side elevational view of the watch band clasp shown in FIG. 1;

FIG. 4 is a right side elevational view of the watch band clasp shown in FIG. 1;

FIG. 5 is a bottom plan view of the watch band clasp shown in FIG. 1; and

FIG. 6 is a rear elevational view of the watch band clasp shown in FIG. 1.

I claim:

The ornamental design for a watch band clasp, as shown.
